Des. 1319

Eliza A. Murdock, of Boston, Mass.
Letters Patent No 1319, dated Oct. 2, 1860.

The schedule referred to in these Letters Patent and making part of the same.

To all to whom these presents shall come:

Be it known that I, Eliza A. Murdock, of Boston in the County of Suffolk, and State of Massachusetts, have invented a new and useful or ornamental design for a Lady's worked promenade or riding hat, and I do hereby declare that the same is fully described & represented in the following specification & the accompanying drawings, of which-

Figure 1. represents a side view of my design.

Figure 2. represents the opposite side thereof.

Figure 3. is a front end view of the same.

The above mentioned hat is made as follows: The body A. of the hat is crocheted or knit in one piece, with a crown a, and rim b.

One side of the hat is provided with a knot and crocheted ornament B. of the form as shown in Fig. 1, and with four or any suitable number of buttons c, placed over it.

On the opposite side of the hat Fig. 2. is an imitation of a feather C, the same being knit by passing the yarn once or twice around the finger while forming the stitches. The hat is also provided with ear pads, D D, extending underneath the rim as seen in the drawings, and a narrow knit band c, which extends across the back of the head and between the ear pads when the hat

2

Dec. 13 19

is in place on the head of the wearer.

Ribbons E, E, are attached to the ear pads for the purpose of securing the hat to the wearers head.

I claim the above described form or design for a knit or crocheted hat, the same being constructed of Berlin or Shetland worsted, of any suitable material capable of being knit into the form as above described, and as shown more particularly by the drawings.

In testimony whereof I have hereunto set my signature this
seventh day of August A.D. 1860.
